GUSTAV TER MEER, OF HANOVER, GERMANY.

CENTRIFUGAL MACHINE.

1,094,230.

Specification of Letters Patent.

Patented Apr. 21, 1914.

Application filed December 10, 1913. Serial No. 805,694.

To all whom it may concern:

Be it known that I, GUSTAV TER MEER, a subject of the Emperor of Germany, and a resident of Hanover, in the Province of 5 Hanover, Prussia, Germany, have invented certain new and useful Improvements in Centrifugal Machines, of which the following is a specification.

This invention relates to certain improvements in centrifugal machines and more particularly to that type adapted for use in the treatment of liquids from which a foam may be readily produced, such for instance as sewage or other liquids containing sapo- 15 naceous ingredients.

My invention resides in the means employed for preventing the formation of froth by the liquid thrown out from the machine and from which the solid or heavier 20 materials have been separated. Some liquids when thrown out over the edge of a part of a machine rotating at high speed and striking the outer casing with considerable force are broken up and converted into foam, 25 which interferes with the operation of the machine. In my improved construction I provide an annular, stationary, upwardly inclined wall closely adjacent to the overflow edge and directly in the path of the 30 liquid. Due to the fact that the inclination of the annular stationary surface is only slightly different from the direction in which the liquid tends to travel as it leaves the overflow edge, and due to the fact that the 35 overflow edge is disposed closely adjacent to this surface, the transfer of the liquid from one to the other is accompanied by but slight loss of momentum in the liquid. Due to the upward inclination of the wall, the tendency 40 of the liquid to travel around this annular stationary wall and outwardly toward the periphery is resisted, not only by the consequent upward movement of the liquid against gravity but also by the friction with 45 the surface over which it is traveling. The speed of the liquid will thus be reduced to such a degree that when it leaves the upper outer edge of the inclined wall the tendency to form a froth in striking the peripheral 50 casing of the machine will be reduced to a minimum.

Reference is to be had to the accompanying drawings in which similar reference characters indicate corresponding parts in 55 the several views and in which,

Figure 1 is a central, vertical section

through a machine embodying my invention. Fig. 2 is a vertical, central, longitudinal section of a portion of the drum on a somewhat larger scale, and showing certain features differing somewhat in detail of construction from that shown in Fig. 1; and Fig. 3 is a vertical section through my improved froth preventer designed for use with a somewhat different form of drum.

The machine shown in these drawings embodies various important and novel features, but in the present application, I have divided out all claims to such features with the exception of those relating to the prevention of foam or froth formation. These other features are reserved for and claimed in my co-pending application, Serial No. 826,868, filed March 24, 1914, for centrifugal machines.

In the specific form illustrated the main 75 rotating parts of the machine are carried by a central vertically disposed shaft 10, supported at its lower end in any suitable form of step bearing 11, and having adjacent its lower end suitable driving connections such 80 for instance as a pulley 12, whereby the machine may be driven at high speed.

Intermediate of its ends the shaft is supported in a suitable bearing 13, and at its upper end it carries a head 14 secured thereto in any suitable manner. As shown the head has a central aperture with a conical seat receiving the conical upper end of the shaft and locked in place by a nut on the upper end of the shaft. The head forms the 90 inner or central core of the separation chamber or drum, and is encircled by the peripheral wall 15 of the drum, which latter is spaced from the head the required distance to leave the annular separation chamber. 95 The head adjacent its lower end has integral therewith or rigidly secured thereto an annular wall 16 constituting the bottom of the separation chamber or drum, and presenting a peripheral face contacting with the inner surface of the peripheral wall. At the upper end of the peripheral wall 15 is a top 100 wall or lid 17 held rigid in respect to the bottom 16 in any suitable manner, as for instance by vertically extending posts 18.

The top wall or lid 17 has a large central opening, through which extends the supply pipe 19 for the material to be treated. At the lower end of the supply pipe are spaced guiding plates 20 and 21 extending 110 outwardly over the head 14 and carrying at their peripheries two cylindrical spaced

plates or walls 22 and 23 which latter terminate at their lower ends adjacent to the bottom wall 16. Thus the material to be treated and which enters through the supply pipe 19 is delivered to the drum closely adjacent the bottom of the latter and in a thin annular stream, but ordinarily not until after the drum or separation chamber including the peripheral wall and the bottom 10 and top walls 16 and 17, have reached the desired high speed of rotation. As the mixed liquid and solid material is admitted the solid or heavier material will be thrown by centrifugal force against the wall 15, 15 while the lighter or liquid portions will collect as an inner or more centrally disposed layer. As the material continues to flow into the drum and the latter continues to rotate at high speed, the drum will eventually 20 become filled to such an extent that for each additional quantity of material entering the machine a corresponding amount will flow over the upper, inner edge of the top wall 17. As this edge is nearer the center of rotation than is the peripheral wall 15, it is evident that it will be the lighter or more liquid portions which will overflow, and that the heavier or more solid materials 25 will remain in the drum. Thus there will be 30 a continuous circulation through the machine, but the heavier particles will be retained. The proper rate of flow of the fluid through the machine determines the capacity of the machine, and is regulated in accordance with the composition of the material to be operated upon and by the completeness with which it is desired to separate the solids from the liquid. The slower the circulation the longer the material will 35 40 stay in the machine and the longer it will be exposed to centrifugal force, thus more solid substance will be deposited and the liquid thrown out over the edge of the top wall will be purer or clearer. The solid 45 material separated by centrifugal force, will settle on the outer or peripheral wall and the resulting layer of the solid material will grow by degrees until the desired thickness has been reached at which time the supply 50 will be shut off. The machine will now contain an outer layer of compact solid material and an inner layer of liquid or semi-liquid material. The innermost layer which extends to the overflow edge may be comparatively 55 clear liquid and ejecting the solid material at this time would result in a simultaneous discharge of the liquid and semi-liquid portions remaining in the drum. In order to remove this liquid and the semi-liquid 60 portions before ejecting the solid or well-dried material I provide a siphon pipe 24 mounted in the top or frame 25 of the machine and extending into the drum with a pivotal support so that its lower end may be swung inwardly to inoperative position 65

adjacent the top of the plate 20, or may be swung outwardly about a vertical axis to the point illustrated in Fig. 1. The open end of the pipe when in the latter position will project into the liquid or semi-liquid layers in the drum and due to the high speed of rotation of the latter this portion will be forced into and up the siphon pipe and will be ejected from the machine through a discharge pipe 26. After the withdrawal of the liquid and semi-liquid portions from the drum by the siphon pipe 24, there remains in the drum only the solid well-dried material packed against the peripheral wall 15. 70 As previously indicated one important 80 feature of my invention resides in the simple means which I employ to permit the rapid and complete discharge of this solid material. This means operates to effect a relative axial movement of the peripheral wall 85 and the top and bottom walls of the drum. As a simple and efficient means for producing this movement I provide the head 14 with a plurality of vertically disposed cylinders 27, each containing a piston 28, the piston rod 29 of which extends down through a stuffing box at the lower end of the cylinder. All of the piston rods at their lower ends are connected to the lower end of the peripheral wall 15 by means of an annular 90 plate 30 or a plurality of separate arms disposed below the bottom 16 of the drum. Extending lengthwise through the main shaft 10 are two liquid passages 31 and 32, one of which is connected by suitable branch 95 passages to the upper ends of all of the cylinders while the other is connected by suitable branch passages to the lower ends of all of the cylinders. Adjacent its lower end the shaft is provided with a sleeve 33 having 100 two annular grooves or passages on the inner surface, one of which communicates with one passage of the shaft and the other communicates with the other passage. The sleeve is nonrotatable and has two fluid supply pipes 34 and 35, connected thereto, one leading to each internal groove or passage, thus fluid may be delivered to the lower ends of all of the cylinders, from the supply pipe 35, or may be delivered through the supply 110 pipe 34 to the upper ends of all of the cylinders, irrespective of the speed of rotation of the shaft. By controlling the flow of fluid through these supply pipes the pistons may be simultaneously forced upwardly or downwardly in their respective cylinders, and the peripheral wall 15, will at the same time be raised or lowered. It will thus be noted that the peripheral wall is raised or lowered by fluid pressure and that its raising or lowering may be accomplished entirely independently of its rotation. The fluid for effecting the movement may be either liquid or gaseous but is preferably a liquid such for instance as oil delivered from a suitable source 115 120 125 130

under pressure, whereby the peripheral wall may be forced up against the top wall with any desired degree of pressure. This pressing of the peripheral wall and the top wall together by means of fluid pressure is an important feature of my invention, inasmuch as it permits the effective sealing of the joint between the lid and the peripheral wall. As shown in Fig. 1 and more clearly in Fig. 2, the top wall is of larger diameter than the peripheral wall and presents on its under surface a seat adapted to receive a gasket 36 against which the peripheral wall may be pressed by the application of fluid pressure to the under sides of the pistons 28. This pressure will of course be proportioned to the centrifugal force exerted on the material in the drum and the resulting tendency of the latter to escape through the joint.

With the bottom wall and the peripheral wall axially movable so as to effect a discharge of the material I secure a tight joint between these walls preferably by means of a packing the operative pressure of which is directly dependent upon centrifugal force. This may be in addition to a suitable gasket to which pressure is applied by the axial movement of the casing. As shown particularly in Fig. 2 the peripheral wall presents a shoulder 37 adjacent its lower end upon which is seated a gasket 38, the shoulder and gasket being so positioned that when the peripheral wall is forced upwardly to bring its upper edge against the gasket 36, the gasket 38 will be pressed against the under surface of the bottom 16.

The bottom wall on its peripheral edge is preferably provided with an annular recess within which is placed a packing engaging with the inner surface of the peripheral wall. This packing is so constructed and so mounted that it is acted upon by centrifugal force and is pressed outwardly against the peripheral wall with a pressure directly dependent upon centrifugal force. This packing may be either of elastic material or of metal or both may be employed if desired. In order that they may be subjected to the action of centrifugal force the packing should not be a single ring, but should be made of sections or should be in the form of divided rings or spirals. As shown in Fig. 2 the bottom wall at its periphery carries two superposed packing rings 39, 39. The packing or the loose weight in the rear thereof has such specific weight that when the machine is in operation the packing will be pressed against the peripheral wall more firmly than is the material within the drum, so that the latter can not escape past the packing.

In the treatment of certain classes of material in my machine the throwing of the liquid against the peripheral wall or casing

of the machine, often results in the formation of undesirable amount of froth. This is particularly true in treating sewage, in which considerable quantities of soap or soapy compounds may be in solution in the liquid.

My present invention resides solely in the means for preventing this froth formation and includes an annular upwardly inclined stationary wall over which liquid must pass before escaping. The frictional resistance encountered, the upward direction of the movement of the liquid and the thinning out of the liquid as it covers the larger area toward the periphery, all retard the flow of the liquid, so that when the liquid escapes from the upper free edge of this stationary wall it has lost to a large extent its velocity and may drop into the receiving chamber or conduit without the formation of froth to any objectionable extent.

In Fig. 1 I have shown the top wall 17 provided with a lip 42 from the free edge of which the liquid is discharged during the operation of the machine. The outer stationary casing 43 of the machine carries an annular inclined wall 44, the lower inner edge of which is slightly below the free edge of the lip 42. Around the outer edge of the wall 44 is an annular trough 45, into which the liquid is eventually deposited and from which it may flow through the contact 46. It will be noted that this wall 44 is stationary and that the liquid thrown on to it from the lip 42 by centrifugal force must travel upwardly at the same time it tends to travel around the wall and that the velocity of the liquid will have been very largely overcome by the time the liquid flows over the outer edge into the trough. Thus the liability of the formation of froth is largely if not entirely eliminated. In Fig. 2 I have shown a slightly modified construction in which the upper, inner edge of the lid is bent outwardly to form the lip 42 and the trough 45 is curved in cross-section, but operates in substantially the same manner as the construction shown in Fig. 1. The same principal of preventing froth formation may be embodied in various other forms of centrifugal machines. In Fig. 5, I have shown a portion of a machine in which the peripheral wall 47 is either permeable or perforated so that the liquid may pass directly therethrough while the solid material will remain within the drum. In this construction I provide an outer wall 48 rigid with the permeable or perforated wall and closely adjacent thereto so that the liquid in being thrown out will only travel a very slight distance before striking this outer imperforate wall. No froth will be formed at this point as the two walls are traveling together. The liquid will flow down the inner surface of the wall 48 and

will then be thrown out on to an annular inclined wall 44 corresponding exactly with the inclined wall 44 shown in Fig. 2. This wall leads to a trough 45 from which the liquid may be discharged. The effect of this annular inclined wall is as previously indicated, to reduce the velocity of the liquid without material froth formation.

As previously indicated the material is 10 discharged from the drum by lowering the peripheral wall and permitting material to be thrown out by centrifugal action. The casing 43 is preferably spaced from the peripheral wall a short distance so that the 15 material may strike this casing and drop down into an annular channel 49 adjacent the base of the machine. An inner wall 50 may be carried by the casing 43, concentric therewith, so as to prevent material from 20 falling into the space beneath the drum and thus interfere with the downward movement of the wall 15. Various mechanisms may be employed for removing the material from the trough 49 but preferably I provide 25 a scraper 51 connected to a worm wheel 53, concentric with the shaft but unattached thereto. The connection may be a plate 54 which will prevent any material from dropping on to the worm wheel. A 30 worm 55 driven in any suitable manner may mesh with the worm wheel and effect the slow rotation of the latter and the scraper so as to deliver the dried material to an outlet conduit 56. This conduit may have 35 a slide valve 57 or any other suitable means for controlling it.

In the operation of my improved machine the successive steps preferably take place substantially as follows: Suitable power is 40 applied to the shaft 10 to rotate the latter at very high speed, and the inlet valve 58 in the supply conduit is opened to permit the admission of the mixed liquid and solid material to be treated. As previously indicated 45 this solid material accumulates against the inner surface of the wall 15 while the liquid overflows from the lip 42 and eventually reaches the discharge conduit 46 while froth is prevented by the plate or wall 44. When 50 the solid material has accumulated to the desired extent the inlet valve 58 is closed and the siphon pipe 24 is rotated about a vertical axis to substantially the 55 position shown in Fig. 1, so that the liquid remaining in the drum and which has not been thrown out from the lip 42 will be drawn off. This liquid which may be comparatively rich in solid material may be returned to the original source of supply to be 60 retreated rather than disposed of with the liquid flowing out through the outlet 46. The pressure below the pistons 48 is now released and pressure is applied to the upper sides of the pistons to force the casing downwardly axially. The solid material will be

thrown out by centrifugal force against the stationary casing 43 and dropped down into the trough 49 from which it is removed by the scraper 51. The peripheral wall is then returned to the position shown in the drawing, the siphon pipe is moved to inoperative position and a fresh supply of material to be treated is admitted by opening of the inlet valve 58. It is of course evident that the timing and controlling of these operations may be done entirely by hand, but I preferably accomplish them automatically. In my co-pending application Serial No. 805,693, filed December 10, 1913, I have illustrated a mechanism which is particularly useful in controlling a machine of the character shown in the present application. The inlet valve 58 may be operated by a piston mounted in a cylinder 59 and the siphon pipe 24 may be moved to operative and inoperative positions by the reciprocation of a piston in a cylinder 60. The mechanism illustrated in my co-pending application above referred to may operate to control the flow of liquid to and from the cylinders 27, 59 and 60 so that the successive operations may be performed in the desired sequence after the desired amount of solid material has accumulated. The length of time required for this to accumulate may be automatically controlled as disclosed in my co-pending application above referred to or may be accomplished manually.

Having thus described my invention, what I claim as new and desire to protect by Letters Patent, is:

1. A centrifugal machine for separating mixtures including foam forming liquids, comprising a drum adapted to receive a stream of said mixture and having a peripheral wall against which the heavier or solid portions of said mixture may collect and be retained within said drum when said drum is rotated at high speed, and an overflow edge over which the foam forming liquid 105 may be thrown out at high speed, an annular trough receiving said liquid and a stationary annular ascending wall receiving said liquid directly from said overflow edge, and delivering it to said trough at such reduced speed that it will enter said trough 110 without foam formation.

2. A centrifugal machine for separating mixtures including foam forming liquids comprising a drum adapted to be rotated at 120 high speed and having a delivery edge from which the foam forming liquid may be delivered by centrifugal force at high speed, an annular trough encircling said drum, and including inner and outer peripheral walls 125 and a stationary annular upwardly and outwardly inclined wall supported by the inner peripheral wall of said trough and extending across the upper edge of the latter, said wall receiving liquid directly from said de- 130

- livery edge without shock and delivering it to said trough at such reduced speed as will prevent the formation of foam as said liquid leaves said wall in said trough.
- 5 3. A centrifugal machine for separating mixtures including foam forming liquids comprising a drum adapted to retain the heavier or solid portions of said mixture, and having an upwardly and outwardly inclined annular overflow lip or flange and a stationary upwardly and outwardly inclined annular wall closely adjacent to said lip or flange, the surface of said wall being at a very slight angle to the direction of flow 10 of said liquid as it leaves said lip or flange and serving to receive said liquid and gradually slow down the movement of the latter and permit it to flow from said wall substantially without foam formation.
- 15 4. A centrifugal machine for separating

mixtures including foam forming liquids comprising a drum adapted to retain the heavier or solid portions of said mixture, and having an overflow edge and a stationary upwardly and outwardly inclined annular wall closely adjacent to said overflow edge, the surface of said wall being at a very slight angle to the direction of flow of said liquids as it leaves said overflow edge and serving to receive said liquid and 25 gradually slow down the movement of the latter and permit it to flow from said wall substantially without foam formation.

Signed at Hanover, Germany this twenty-sixth day of November, A. D. 1913.

GUSTAV TER MEER.
